UNITED STATES PATENT OFFICE

2,264,081

GASEOUS DISCHARGE LAMP

Kurt Jost, Berlin-Pankow, and Wolfgang Thonet, Berlin-Wilmersdorf, Germany, assignors to General Electric Company, a corporation of New York

Application March 14, 1941, Serial No. 383,404
In Germany March 7, 1940

3 Claims. (Cl. 176—124)

This invention relates to electric discharge lamps and more particularly to that type of projection lamp shown in the United States Patent No. 2,116,702 issued to Kern et al. and assigned to the assignee of the present invention.

The above-mentioned patent is directed to gaseous electric discharge lamps, preferably of the high-pressure type, with activated electrodes heated by the discharge and a discharge bulb in which the several electrodes are arranged so closely around the center of gravity of the light source and fed by the current in such a way that several discharge arcs playing between the electrodes produce a uniform illuminating surface. In one of the disclosed forms the discharge bulb may contain two opposed parallel rows of two or more electrodes each of which rows produce cross arcs between diagonally disposed electrodes in addition to the parallel arcs between directly opposed electrodes. This is accomplished by using either several current sources, for example several secondary windings of a transformer, or by using phase-displacing impedances. In the latter case the arcs are displaced in phase and, although they give the impression of a uniform illuminating surface to the naked eye owing to their rapid succession, they might be objectionable in various fields of application, for example in motion picture projection, owing to the stroboscopic effect. Now we have found that it is possible to obtain a high-pressure discharge lamp of the aforesaid type which is free of these objections by employing a novel arrangement of the electrode and circuit elements.

Accordingly it is an object of our invention to provide a lamp of the aforesaid type which shall be free of the aforesaid objections and which may be operated from a single power source of either direct or alternating current. Further objects and advantages of our invention will appear from the following detailed description and accompanying drawing.

Generally speaking, the objects of the invention are accomplished by arranging the opposed parallel rows of electrodes in such a manner that the distance between the two rows of electrodes is made at least twice the distance between the electrodes of a single row and, in addition, by making the series resistance of any one glow electrode twice as large as the series resistance of an adjacent electrode of the same row.

Referring to the drawing, Figures 1 and 2 illustrate alternative forms of discharge lamps designed according to the invention, the arcs being indicated by dashes.

In the 220 volt D. C. lamp shown in Fig. 1, the spherical quartz bulb 1 contains two rows of electrodes 2, 3 fed by the discharge, each row having four electrodes which are preferably of the activated type. The spacings between the electrodes of one row are about 6 mm. between the tips where the arc plays while the distance between the two rows of electrodes is about 15 mm., that is, at least twice as large.

Each of the electrodes 3 of the lower row is connected through a vacuum-tight sealed molybdenum foil 4 and a series resistance 7 to the other terminal of a D. C. source. The series resistance 7 of the first electrode of the upper row and also the series resistance 5 of the last electrode of the lower row has a resistance of about 4 ohms, while the magnitude of the series resistances of the other electrodes is only 2 ohms. When such a lamp, which contains as usual a fundamental filling of rare gases and mercury which is completely evaporated during the starting process, is switched on, the four parallel arcs 8 are produced. The difference in the chosen values of the series resistances causes such voltage drops across the series resistances and consequent potential differences between the electrodes that for the given electrode spacings the three additional cross arcs 9 are produced. These interconnect the four parallel arcs 8 as shown. All the seven arcs carry the same discharge currents of about 6 amperes at an operating vapor pressure of about 25 atmospheres. The seven high-pressure arcs cause a remarkably uniform 15 x 18 mm. illuminating surface of very high intensity.

Fig. 2 shows a high-pressure 110 volt discharge lamp with two rows of three electrodes each. In this case the series resistances are of such magnitude that the series resistances 7 of the glow electrodes of the upper row are in the ratio of 3:1:3, and the series resistances 5 of the corresponding opposite electrodes of the lower row are as 1.5:3:1.5. The magnitude of the resistances may be, for example, 1, 1.5 and 3 ohms respectively. The spacing between the rows of electrodes is 10 mm.; the spacings between the electrodes of the same row are about 4 mm. In this lamp the two cross arcs strike at the middle upper electrode.

In both examples shown in the drawing the series resistances are of such magnitude that the voltage drops across the upper and lower series resistances are the same. The same discharge configurations may naturally also be obtained when the series resistances of the electrodes of

the lower row are reduced and the series resistances of the electrodes of the upper row are increased in proportion. The potential of the illuminating field is then brought closer to the potential of one of the poles of the current source. When an A. C. source is used instead of a D. C. source, choke coils or capacitors may be used instead of ohmic resistances, the discharge arcs produced then all being in phase.

It will be understood that many modifications of the described lamps may occur to those skilled in the art to which they relate. Thus, since it is not necessary that the electrodes be disposed in parallel rows, any number of them may be arranged in any configuration which will permit the described cross-arcs to be established. Further, by other choices of resistance values and electrode spacings within the prescribed conditions many different cross-arc configurations may be obtained. All these we aim to include within the scope of the appended claims.

What we claim as new and desire to secure by Letters Patent of the United States is:

1. In combination, a gaseous electric discharge device comprising a sealed envelope and opposed series of two or more electrodes each in said envelope and so positioned that electrical discharges between the various electrodes produce a high intensity source of light covering a major portion of the area bounded by said electrodes, a source of power, a set of impedances in series connection with each of said electrodes of both series of electrodes, means for electrically connecting the electrodes of one said series through their impedances to one pole of said source, and means for electrically connecting the electrodes of another of said series through their impedances to another pole of said source, the distance between said series being at least twice as great as the distance between individual electrodes of each series, and said impedances being so proportioned that at least one of said impedances in at least one of said series is approximately twice as great as an adjacent impedance in the same series whereby cross arcs are formed between said series of electrodes.

2. In combination, a gaseous electric discharge device comprising a sealed envelope and opposed

series of two or more electrodes each in said envelope and so positioned that electrical discharges between the various electrodes produce a high intensity source of light covering a major portion of the area bounded by said electrodes, a source of power, a set of impedances in series connection with each of said electrodes of both series of electrodes, means for electrically connecting the electrodes of one said series through their impedances to one pole of said source and means for electrically connecting the electrodes of another of said series through their impedances to another pole of said source, the distance between said series being at least twice as great as the distance between individual electrodes of each series, and said impedances being so proportioned that the impedance in series with the first electrode of one series and the impedance in series with the last electrode of another series are at least about twice as large as the impedance in series with any other electrode in the same series whereby cross-arcs are formed between said electrodes.

3. In combination, a gaseous electric discharge device comprising a sealed envelope and opposed series of three or more electrodes each in said envelope and so positioned that electrical discharges between the various electrodes produce a high intensity source of light covering a major portion of the area bounded by said electrodes, a source of power, a set of impedances in series connection with each of said electrodes of both series of electrodes, means for electrically connecting the electrodes of one said series through their impedances to one pole of said source, and means for electrically connecting the electrodes of another of said series through their impedances to another pole of said source, the distance between said series being at least twice as great as the distance between individual electrodes of each series, and the said impedances in one series being in the approximate ratio 3:1:3 and the impedances connected to corresponding electrodes in another series being in the approximate ratio 1.5:3:1.5 whereby cross arcs are formed between said electrodes.
